EASY OPENING CONTAINER

William F. Punte, Syracuse, N. Y., assignor to
Continental Can Company, Inc., New York,
N. Y., a corporation of New York

Application July 3, 1930. Serial No. 465,742

1 Claim. (Cl. 220—54)

The invention relates to new and useful improvements in an easy opening container, and more particularly to the construction of an inserted reclosure collar used in connection therewith.

An object of the invention is to provide an easy opening container of the rip strip type having an inserted reclosure collar, the edge of which is formed by pressure applied to the metal so that

10 said edge is smooth and unbroken.

A further object of the invention is to provide a container of the above type wherein the collar is substantially of uniform thickness throughout.

A still further object of the invention is to provide a container of the above type wherein a collar formed as stated above is attached to the body of the container and overlies the rip strip, and also a collar attached to the end of the container and overlaps the first named collar.

20 These and other objects will in part be obvious and will in part be hereinafter more fully disclosed.

In the drawing:—

Figure 1 is a sectional view through a container embodying the improvements prior to the removing of the rip strip.

Figure 2 shows a portion of the container with the rip strip removed and the cover lifted from the container.

30 Figure 3 is an enlarged vertical sectional view through the reclosure collar which is adapted to be attached to the body of the container.

Figure 4 is a view of a portion of the inserted collar showing the ends joined by securing the 35 same in abutted relation to each other.

The invention is directed to the construction of an inserted reclosure collar used in connection with an easy opening container of the rip strip type. It has been a common expedient to score the body of a container along spaced lines to provide a rip strip which is torn out by the use of a key for opening the container. It has been also a common expedient to insert a collar in the body of the container so that it overlies a portion of the rip strip and aids in the reclosing of the container after the rip strip has been removed. Collars of this character are usually made of metal which is cut of proper width, and this leaves a raw edge of metal which if not concealed is liable to cut the hand of the user of the container. Another common expedient has been to roll the edge of the collar in order to conceal the raw edge of the metal. Various other ways have been employed for providing a smooth edge at the top of the container after it is open, and a smooth edge at

the lower part of a portion carried by the detached end. The present invention has to do with the construction of a reclosure collar wherein the collar is formed and the edges shaped by pressure applied to the metal, so that the metal is caused to flow in the forming of the edge and thereby a smooth, unbroken edge is provided which will not in any way injure the hands of the user.

In the accompanying drawing one form of container is shown having the improved reclosure collar applied thereto. The container consists of a body portion 1 which is joined to an end 2 by double seam 3. There is another end at the lower end of the container likewise joined to the body of the container. While the end is shown as secured by a double seam it may be secured in any suitable way in order to provide a hermetically closed container. The body as shown is provided with an inwardly projecting bead 4.

65 The body portion is also provided with a score line 5 and a score line 6 setting off the rip strip 7. The score line 6, as illustrated, is directly beneath the double seam 3 so that when the rip strip is torn away the raw edge of the metal is protected by the projecting portions of the seam.

70 As shown in the drawing, the inserted reclosure collars are used. One is indicated at 8 and the other at 9. These collars, except as to cross sectional shape, are similar in construction. Each 75 collar is formed from a strip of metal by applying pressure thereto so as to cause the metal to flow into the desired shape. This is preferably accomplished by rolling the metal into the desired shape for a collar, then cutting the metal 80 into suitable lengths and joining the edges to form the collar. In Figure 3 an enlarged cross

85 sectional view of the collar is shown, and it will be noted that the side faces 10 and 11 are substantially parallel. The upper edge as shown in 90 this view is rounded as indicated at 12. Likewise the lower edge is rounded as indicated at 13. The edges may be otherwise shaped than rounded.

95 The essential features, however, consist in the subjecting of the metal to pressure so as to cause the metal to flow to form the edges so that the edges will be smooth and unbroken, as distinguished from a cut edge or a torn edge. As shown in Figure 4 the ends are abutted as indicated at 14 and are welded. These ends may 100 be secured in any desired way, but preferably they are abutted so that the collar will be of uniform thickness throughout its entire extent. The collar 8 is bent intermediate its side edges as indicated at 15, so that the upper section 8a is 105

110 indicated at 16, so that the upper section 8a is 115

offset slightly from the lower section 8b. This collar 8 is inserted in the container during the manufacture thereof, and when there is a bead in the container it is preferably disposed so that the lower edge of the collar rests against said bead. The bead serves solely as a support for the collar, and does not in any way secure the collar to the container. The collar may be secured to the body of the container in any desired way. 10 As shown in the drawings it is made of such size that when forced into the container it will frictionally grip the container wall and be held in place. It may be secured by soldering or by bending the metal of the collar or the metal of the container. It is essential that it shall be firmly attached to the body of the container and become a part thereof, so that when the rip strip is removed this collar becomes the upper edge portion of the body of the container and provides a smooth edge which will not in any way injure the hands of the user contacting therewith.

The collar 9 as shown in the drawing is clamped between the wall of the body and the well 16 formed by a depression in the collar. The collar is inserted between these walls, and when the double seam is formed the pressure exerted on the metal in the rolling of the double seam will cause these walls to firmly grip the collar 9. The 30 collar 9, therefore, becomes firmly attached to the end which is separated from the body when the rip strip is torn away. It will be understood that this collar may be otherwise secured to the end which is separated from the body.

35 When the rip strip is removed as shown in Figure 2 then the end which is separated from the body may be lifted from the container. This makes an easy way of opening the container. The container can be reclosed by slipping the 40 collar 9 down over the collar 8. These collars

overlap before the rip strip is removed, and therefore serve as a support during the turning of the key to tear away the rip strip. They also serve to retain the material in the container during the opening of the same.

While the container has been shown as provided with two inserted collars, it will be understood that other means may be provided on the separated end for cooperating with the collar on the body for reclosure. On the other hand other means may be formed in the body wall for cooperating with the improved reclosure collar attached to the end which is released from the body. It is understood, therefore, that the invention is directed broadly to the construction of a reclosure collar, and that this reclosure collar may be used with various types of easy opening containers.

Having thus described the invention, what is claimed as new and desired to be secured by Letters Patent, is:—

An easy opening container having score lines formed in the body adjacent one end thereof for providing a rip strip, an inserted reclosure collar attached to the body of the container below the lower score line and projecting above said score line, said collar being formed by pressure applied to the metal whereby a smooth and unbroken edge is provided, and a collar attached to the end which is to be separated from the body by the removal of the rip strip, said last named collar being formed by pressure applied to the metal whereby a smooth and unbroken edge is provided, said collar attached to the body of the container having the portion thereof above the lower score line inset away from the wall of the container, the thickness of the collar attached to the end whereby said collar on the end may extend down over the collar on the body.
